UNITED STATES PATENT OFFICE.

MARTIN R. ETHEridge, OF LYNN, MASSACHUSETTS.

LASTING-MACHINE.

SPECIFICATION forming part of Letters Patent No. 392,193, dated November 6, 1883.

Application filed November 30, 1885. Serial No. 184,258. (No model.)

To all whom it may concern:

Be it known that I, MARTIN R. ETHEridge, of Lynn, in the county of Essex and State of Massachusetts, have invented certain new and useful Improvements in Lasting-Machines, of which the following is a specification, reference being had to the accompanying drawings, making a part hereof, in which—

Figure 1 is a plan with the crimping jaws removed on the right-hand side. Fig. 2 is a section on line x x of Fig. 4. Fig. 3 is a section on line y y of Fig. 1. Fig. 4 is an elevation. Fig. 5 is a bottom plan of the crimping-jaws. Fig. 6 shows the jaw B' or B^2 and its rubber spring. Fig. 7 is a section across the toe; Fig. 8, a cross shank; Fig. 9, a cross-heel shoe clamped and crimped—that is, both jaws closed upon the shoe and last.

My invention relates to machines of that class described in my patent, No. 269,841, dated January 2, 1883, and consists in certain improvements, which will be clear from the following description and claims.

The crimping-jaws A A' A^2 have each a dovetail groove across its lower face, and this groove fits upon a dovetail rib formed upon the carriers a a' a^2 , which are fast upon the levers A . The purpose of the dovetail grooves and ribs is that the crimping jaws may be readily removed and replaced by others to suit a different style of shoe, or to change from rights to lefts. The jaws A A' A^2 are held in place by the rod a^3 , which enters a groove, a^4 , across the ribs on the carriers a a' a^2 and the groove a^5 across the lower face of the jaws A A' A^2 , these grooves a^4 a^5 being coincident when the crimping-jaws are in place in the carriers. This feature of my invention consists in the combination of the crimping-jaws with their levers or carriages by means of intermediate carriers, instead of connecting them directly with their levers, as in my former patent, its main advantage being that the crimping-jaws are far more readily changed than in my former machine.

The clamping-jaws B B' B^2 have each a dovetail rib across it, to secure it to its carrier b b' b^2 , so that the clamping-jaws can be readily removed and replaced. The carriers b b' b^2 are supported by the main carriers a a' a^2 , by means of the rods b^3 , and are held in proper relation to the carriers a a' a^2 by the springs b^4 and rods

b^5 . This feature of my invention consists in the combination of the clamping-jaws with carriers, instead of directly with the crimping-jaws, as in my former patent.

The toe and heel clamps B' B^2 are each composed of the parts 1 and 2, (see Figs. 7 and 9, 1 and 6, the latter being a detail to show this feature,) connected so that the part 1 may move slightly endwise in the part 2 against a spring, 3, in order to suit slight variations in the length of the shoe to be lasted—for example, variations in the length of lasts intended to be of the same length and variation in length caused by the difference in the thickness of 65 the stock. This is an important feature of my invention, as it is an automatic adjustment which I have found practically essential for the best operation of the machine. The working-faces of the jaws B' B^2 are the counterparts 70 of the toe and heel of the shoe to be lasted, and when in operation cover those parts of the shoe, the upper surfaces of these jaws being then on a level with the surface of the inner sole, as will be clear from the diagrams 75 Figs. 7, 8, and 9, which are sectional views showing the shoe when held by the jaws. The shank-jaws B B are faced with vulcanized rubber, 4, the upper surface of the rubber being also parallel with the shank part of the inner 80 sole when on the last, and these rubber cushions 4 are crowded upon the shank portions of the shoe to be lasted as the clamping-jaws move toward one another until the clamping-jaws are held stationary by the resistance of 85 the shoe between them; but as the crimping-jaws advance, the projections 5 on the crimping-jaws A press against the cushions 4, and thereby force the upper-leather close about the whole shank portion of the shoe. (See Fig. 90 8.) This feature of my invention—namely, the cushioned shank-jaws in combination with the rigid heel and toe-jaws—is a vital improvement on my former machine, in which all three jaws were rigid.

The back part or cone of the last rests upon the top of post D, and the last is centered endwise by the curved recess in the heel-piece f on the end of the slide F. The forward part of the shoe rests upon the toe-rest G, which is free to slide sidewise upon post G'. Both posts D and G' are adjustable endwise to bring

the shoe to the proper relation to the jaws, and also toward and from each other for different lengths of shoe, said adjustments being preferably obtained, as shown in Fig. 3, where 5 posts D and G' are shown with tangs which enter recesses in the sliding supports G², the hollow portions of which are exteriorly threaded and provided with nuts g', which, when turned in one direction, engage shoulders g³ on the posts and so carry them upward. Supports G² slide in dovetailed ways (see Fig. 2) in the frame of the machine, and are preferably provided with clamps g, by means of which the sliding supports G² are clamped 10 in their ways. The heel-piece f and slide F, while not essential, yet aid the operator. The toe-rest G with a slight sliding motion is new 15 with me.

To adjust for different sizes or lengths of 20 shoes, the carriers a' a² are slid on the ends of levers A³ and held by the pins a⁶, which pass through holes in one flange of the carriers and crimping-holes in the levers. The extra row 25 of holes in the carrier a' (shown in Fig. 4) is for adjustment for box-toes. This combination of the carriers a' a², with the levers A³, and both the clamping and crimping jaws, so that the heel and toe jaws may be adjusted for 30 different lengths of shoes toward and from the shank-jaws, is also a feature of my invention, the difference between my present combination and that shown in my former patent being that there were no carriers for the crimping-jaws in my former patent.

35 Another important improvement over my former machine consists in the mechanism for giving motion to the jaws—that is, the right and left screw instead of the treadle-lever or windlass shown in my former patent. This 40 screw is marked H, and controls the jaws by means of the nuts h h', mounted in the levers A³, as is best seen in Fig. 2. Instead of the levers, sliding carriages may be used, as will be obvious, but the levers are practically better. The nut h is of larger internal diameter than h' for convenience in putting the machine 45 together.

Another feature of my invention is an automatic stop mechanism in combination with the 50 jaws, whereby the motion of the jaws at each extreme is caused to unship the driving-pulley. Both pulleys J J' are rotated constantly, but in opposite directions, so that the screw II will be rotated in one direction when the cone 55 J² is in contact with pulley J, and in the opposite direction when it is in contact with the pulley J', and these pulleys J J' are moved sidewise by the double lever J³, which is controlled by the rod j. This rod j has two adjustable stops, j' j'', upon it, which act with the bracket j³, which is fast to the lever A³, so that when the lever is in the position shown in Fig. 2 the bracket j³ has forced stop j'' down far enough to move rod j and lever J³ into position 60 to free both pulleys J J' from cone J²; but when lever A³ is at its other extreme (that is when the crimping-jaws A' and A² are nearly

in contact with the opposite corresponding crimping-jaws) the bracket j³ will raise rod j by contact with stop j', and thereby hold cone 70 J² out of contact with pulleys J J'.

The operation is as follows: The last is placed in the upper, as in hand-lasting, the upper being drawn over the last at the toe with hand-pinchers and secured to the inner sole at the toe in the usual way. The last with the upper thus arranged upon it is then placed in the machine with the cone of the last resting upon the part D and the toe part of the last upon the toe-rest G, both of which are first properly 80 adjusted. This brings the last with the upper upon it between the clamping-jaws B B' B². The operator then presses his toe upon the pedal k of lever K, and thereby forces pulley J into contact with cone J², and the jaws 85 B B' B² move toward the last, the cushions of the shank-jaws B pressing the upper upon the last at the widest part of the shank of the last, and the toe and heel jaws B B' B² also pressing the upper close upon the last. The attendant uses the ordinary hand-pinchers to strain the upper around the last as soon as he perceives that the clamping-jaws have got a sufficient hold of the last and upper, unshipping the friction-clutch when necessary in order to get time to do this.

One of the chief merits of my improved machine is that it presents the shoe to the workman and holds it to the best advantage for a rapid and effectual use of the hand-pinchers, 100 and the clamping-jaws instantly and perfectly hold the upper in place whenever it is strained by the hand-pinchers, and while this is in a measure true of my former machine, yet the operation of my present machine is in these 105 respects so much more complete as to be practically different, owing, mainly, to the fact that the shank-jaws are elastic cushions, but partly to the fact that the toe and heel jaws can yield lengthwise. When the upper is thus drawn 110 close about and strained upon the last, (as will be understood by all skilled lasters,) the machine is again started and the crimping-jaws force the upper over the corner of the inner sole and close down upon the inner sole, but 115 yet leave the edges of the upper free to be hammered, tacked, and trimmed, or otherwise prepared to receive the filling and outer sole.

What I claim as my invention is—

1. In a lasting-machine, the combination of 120 the crimping-jaws A A' A² and their carriers a' a², the crimping-jaws and their carriers being held together by dovetailed ribs in one and dovetailed grooves in the other, and a rod, a⁶, through the dovetailed ribs and grooves, 125 substantially as and for the purpose set forth.

2. In combination, clamping-jaws B B' B², carriers b' b², and carriers a' a², the carriers b' b² being mounted upon springs which allow the carriers a' a² to move toward the 130 last after the clamping-jaws have engaged the upper on the last, substantially as and for the purpose set forth.

3. The clamping-jaw herein described, com-

posed of parts 1 and 2, and a spring, 3, interposed between the parts 1 and 2, the part 1 sliding on part 2, all arranged and operating so that the jaw may yield slightly endwise, 5 substantially as described.

4. The cushioned shank-jaw B, in combination with the non-cushioned toe and heel jaws B' B², substantially as described.

5. The cushioned shank-jaw B, in combination with the crimping shank-jaw A and the projection 5, whereby the cushion 4 is forced against the upper, not only by the forward motion of the shank-jaw, but also by the motion of the crimping-jaw over the shank-jaw, substantially as described.

6. In a lasting-machine, the combination of toe-rest G and its post G', toe-rest G being movable sidewise on post G', substantially as described.

7. In combination, levers A³, carriers a a' a², 20 crimping-jaws A A' A² and clamping-jaws B B' B², the carriers a' a² being adjustable in the levers A³ toward and from the carriers a, and both sets of jaws A' A² and B' B² being adjusted by adjusting the carriers, substantially 25 as described.

8. The crimping-jaws A A' A² and clamping-jaws B B' B², mounted on levers A³, in combination with the right and left screw H, substantially as described.

9. In combination, clamping and crimping jaws, levers A³, bracket j³, stops j' j², with the clutch mechanism and its rod, substantially as and for the purpose set forth.
